UNITED STATES PATENT OFFICE.

GEORGE B. SMITH, OF WALDWICK, NEW JERSEY.

GAME.

1,134,922.

Specification of Letters Patent.

Patented Apr. 6, 1915.

Application filed December 10, 1914. Serial No. 876,420.

To all whom it may concern:

Be it known that I, GEORGE B. SMITH, a citizen of the United States, and a resident of Waldwick, in the county of Bergen and 5 State of New Jersey, have invented a new and Improved Game, of which the following is a full, clear, and exact description.

This invention relates to games, and particularly to a game adapted to be played by 10 a number of players, and has for an object the provision of an improved arrangement whereby all of the players have an equal chance but where an unwise move by an opponent will be liable to produce disastrous 15 consequences.

Another object in view is to provide an improved game wherein two or more may play at the same time with movable men adapted to act on the order of checkers but 20 with different moves so that more than two persons may play and have equal chances of winning.

A further object of the invention is to provide a game in which men are moved 25 from one point to the other across a given board, the board being provided with a central battleground, and with side fields from which the various players move their men during the playing operation.

30 In the accompanying drawings—Figure 1 is a top plan view of a board formed according to the present invention; Fig. 2 is a top plan view of the men used on the board shown in Fig. 1.

35 Referring to the accompanying drawings by numerals, 1 indicates a board which may be of any desired material, and on which is arranged a plurality of blocks as shown in Fig. 1. These blocks are made alternating, somewhat on the order of the arrangement of the black and white spots on an ordinary checkerboard. The checker arrangement is so constructed as to provide a central battleground 2 for a game, and side fields 3, 4, 5 and 6. Any desired number of colored blocks 7 may be arranged in the battlefield 2 and spaced apart by the usual white blocks 8, while in the various fields 3 to 6, inclusive, a number of rows of blocks 50 7 are provided, a desirable number of rows being four, though a greater or less number could be used. A pair of lines 9 and 10 are provided for dividing the battleground 2 and practically assigning certain sections to 55 the respective side fields 3, 4, 5 and 6. The battleground 2 is also separated from the

side fields by a line 11, with a second line 12 arranged one block therefrom for providing a central section used in playing certain variations of the game. The game 60 is adapted to be played by a number of persons at one time, as for instance two, four or five. In playing the game the men 13, 14, 15, 16 and 17 are used for the first part of the game and the men 18, 19, 20, 21 and 65 22 are used as kings during the latter part of the game whenever a player wins a certain number of points.

Various rules may be provided without departing from the spirit of the invention. 70 For instance, when only two players are using the board the battleground 2 is used as an ordinary checkerboard, though if desired other arrangements may be used, as for instance the use of the fields 4 and 5, one 75 field acting against the other. When four persons are playing and acting independently three rows of men are first arranged in each of the fields, the same occupying the three outer rows of blocks. Various rules 80 may be provided controlling a game of this kind, a desirable rule being that the players of any given field, as for instance field 5, must play toward field 4, while field 4 must play toward field 3 and so on. When the 85 field 5 is playing toward field 4, the men cannot pass line 9, while the men of field 4 cannot pass line 10. The men playing in a game of this kind will have the right to move in two directions on the order of 90 the game of checkers, and in addition will be allowed to move backwardly when entering the opposite field, that is, they will be allowed to move toward the outer edge of the opposite field in any direction which 95 will lead them to said edge. When four parties are using the board and are playing partners, the partners will use, for instance, fields 3 and 5, while the opposite partners will use fields 4 and 6. When playing in 100 this order the field 5 may play against either or both of the fields 4 and 6, but cannot move past that part of lines 9 and 10 within the angle formed by the points 23, 24 and 25. The other fields are given a similar 105 privilege in respect to battleground 2 in front thereof. When any of the men of either side reach the last row of blocks or king row of the opposite party, one of the kings 18 to 20, inclusive, is substituted for 110 the men used. For instance, if the block 13 had reached the king row of the opposite

party the same would be removed and block 22 substituted therefor, which would be what is known as a rover, and allowed to move in any direction on the entire board.

5 Where five persons are designed to play at one time one party may use the blocks in the central section provided by line 12. A man is provided on each block while the various fields 3 to 6 are provided with two 10 rows of blocks or men. This form of game is one of elimination, and the idea is to consider the men within line 12 as kings and capable of moving in any direction, but incapable of going beyond the line 11. The 15 various men in the fields are capable of moving only in two directions. In this particular way of playing a game with the present invention four of the players use the fields 3, 4, 5 and 6, and the fifth player 20 uses the central section.

Various ways of playing the game have been set forth, but it will be evident that other forms could be used without departing from the spirit of the invention. Not 25 only has a central section been provided but wings or fields so that a comparatively large number of players may play the game at the same time. In addition to these features lines 9 and 10 co-act with the side 30 fields for producing a structure which causes the game to be played properly in a certain manner. In playing the game known as

checkers or other similar games usually only two can play at one time, but according to the present invention the principles of these 35 former games have been embodied in a single board which will present substantially the same interest as presented in these former games while allowing a variety of numbers of players to play at the same time. 40 Additional interest has also been provided by multiplying the players as the same will naturally cause a number of moves to be watched by each player instead of the moves of a single opponent. 45

What I claim is—

A game comprising a plurality of movable men, a central checkered section, a plurality of side checkered sections arranged so that men on the side sections may move on to the central section, and means arranged on the central section for dividing the same into as many parts as there are side sections so as to control or limit the amount of movement of the men from the side sections 50 on the central section. 55

In testimony whereof I have signed my name to this specification in the presence of two subscribing witnesses.

GEORGE B. SMITH.
